UNITED STATES PATENT OFFICE.

GEORGE FRANCIS GRAY, OF PITTSBURGH, PENNSYLVANIA.

LIGHTNING ARRESTER.

1,407,061.

Specification of Letters Patent. Patented Feb. 21, 1922.

Application filed January 11, 1919. Serial No. 270,688.

To all whom it may concern:

Be it known that I, GEORGE FRANCIS GRAY, a citizen of the United States, residing at Pittsburgh, in the county of Allegheny and 5 State of Pennsylvania, have invented certain new and useful Improvements in Lightning Arresters, of which the following is a specification.

My invention relates to improvements in 10 lightning arresters, and it consists in the combinations, constructions and arrangements herein described and claimed.

An object of my invention is to provide a 15 lightning arrester of simple construction, which is easily assembled and cheap to manufacture, for use principally on low voltage circuits, such as railway-signal, telephone, fire-alarm, telegraph, and similar lines.

A further object of my invention is to provide 20 a lightning arrester of the vacuum type, whose electrodes may be readily spaced apart the proper distance for the most efficient working of the device.

A further object of my invention is to provide 25 a lightning arrester which may have a relatively short spark gap without the danger of short circuits around the gap, owing to the provision of novel means for preventing such short circuiting.

30 A further object of my invention is to provide a lightning arrester having electrodes shaped to give a selective path which is most suitable for the exact gas pressure in the device.

35 Other objects and advantages will appear in the following specification, and the novel features of the invention will be particularly pointed out in the appended claims.

My invention is illustrated in the accompanying drawing, forming part of this application, in which—

Figure 1 is a sectional view showing half of the lightning arrester in perspective;

Figure 2 is a view showing the means for 45 holding or mounting the device;

Figure 3 is a sectional view of a modified form of the device;

Figure 4 is a sectional view of a modified form of the spacing plate or disc;

50 Figure 5 is a plan view of another modified form of spacing disc; and

Figure 6 is a detailed sectional view showing the alinement of the rounded electrodes with the surfaces of the spacing disc.

In carrying out my invention, I provide 55 two metal punchings A, B, respectively, such as those shown in Figure 1. These punchings are similar in shape. Each is provided with a circular body portion 1, having an inwardly extending ring 2, provided with an outwardly turned flange or 60 rim 3. Each of the members A and B carries an electrode embodied in a central electrode portion 4, formed by spinning, or otherwise fashioning the metal body portion. The tips of the electrodes are 65 preferably rounded, and the inner hollow portions of the electrodes form sockets 5, by means of which the device may be held or mounted in a holder.

A circular spacing plate 6 is provided, this plate consisting of mica, or other suitable insulator, having a central opening 7. Its preferred construction is that shown more in detail in Figure 4. The cup-shaped electrode-bearing plates A and B, together with the spacing plate 6, are sealed in position along their edges with a suitable insulating varnish or compound 8, and then with a moulded material 9, such as bakelite, to give 80 mechanical strength. After assembling the parts, the interior of the chamber thus formed is exhausted, and the opening 10, by means of which the air is exhausted, is sealed by soldering 11, or in any other suitable 85 manner.

In use, the unit is mounted in a convenient holder, such, for instance, as that shown in Figure 2. In this figure, a base 12 is provided with metal springs 13, held by binding 90 posts 14, each of the springs having a curved portion 15, arranged to enter a portion of the socket 5, so as to hold the lightning arrester in position, and at the same time to provide an effective electrical connection. 95

A unit thus formed is of very simple construction, easily assembled, and cheap to manufacture. In use the unit serves to connect the circuit to be protected, as, for instance the wire 17, to the earth, the lightning 100 discharge escaping to earth by jumping the vacuum gap between the electrodes in the well known manner.

In Figure 3, I have shown another form of the device in which the electrode-holding 105 members A and B are in the form of long cups. Disposed within these cups are cup-shaped electrodes 20, having rounded ends

21, facing the opening 7, in the disc 6. In this form of the device, the adjustment of the electrodes to the desired distance apart may be accomplished by pushing them into 5 the cup-shaped holders A' and B' to the desired distance, the electrodes being arranged to frictionally engage the interior walls of the retainer so as to firmly hold them in position. For ordinary use it is 10 preferable to have the rounded ends of the electrodes in alignment with the surfaces of the spacing disc 6.

In Figure 4, I have shown a preferred form of plate for spacing the electrode retainers apart, which is especially desirable 15 for use in providing high insulation resistance when the device is subjected to many heavy discharges. To this end the plate, which I have denoted in general by 6^a, is 20 in fact, made up of a plurality of layers such as those shown at 6^a, 6^b and 6^c, these layers having holes 6^x and 6^y of different diameter, so as to provide long leakage surfaces. This 25 construction also has the additional function of preventing the condensation of metallic vapors. I have found by experience that metallic vapors, which condense on exposed surfaces, do not penetrate into deep, narrow recesses, and for this reason 30 such construction provides additional insulation.

In the use of lightning arresters on railway signalling circuits, unusual precautions are required to prevent short circuiting the 35 gaps by the fusing of the electrodes with extra heavy discharges. In such case, tips of special metal, such as carbon, tungsten or special brass, may be attached to serve as arcing points, and in addition the spacing disc, instead of having one large, central opening, may be perforated with a 40 number of small holes. In Figure 5, I have shown a spacing disc 6^a which is provided with an area having small holes 24 through which the discharge may take 45 place. These holes are so small, however, that they prevent any of the melted metal from short circuiting the two electrodes, since the drops of the melted metal would 50 be too large to pass through the openings.

In order to provide for some variation in gas pressure, it is desirable to have the opposing electrodes somewhat rounded, as 55 in Figure 1. It is well known that for any given gas, the product of the pressure times the gap is constant for minimum sparking voltage, and as the pressure varies, a suitable gap is provided by the spherically shaped electrodes.

60 1 claim:

1. In a lightning arrester, a pair of cup-shaped members having their open ends facing each other and having electrodes, an insulating spacing plate disposed between the

opposed edges of said cup-shaped members, 65 and means for securing the parts in position.

2. In a lightning arrester, a pair of cup-shaped electrode carrying members disposed with their rims facing toward one another, a perforated spacing plate disposed between 70 the opposed edges, and insulating retaining means for securing the parts in position.

3. In a lightning arrester, a pair of conducting cup-shaped electrode carrying members arranged to face one another, an insulating, perforated, spacing plate disposed between the opposed edges of said cup-shaped members, and insulating plastic material for 75 securing the edges of said plate and said members together. 80

4. In a lightning arrester, a pair of oppositely disposed, cup-shaped electrode carrying terminals having their open ends facing each other, an insulating plate disposed between the edges of said opposed terminals, 85 and means for securing the edges of the plate and the terminals together and for insulating said terminals from one another.

5. In a lightning arrester, a pair of opposed cup-shaped conducting members, electrodes carried by said members and spaced apart to provide a spark gap, an insulating plate disposed between the edges of said members, means for securing the edges of the plate and the edges of the members together, said means also constituting an insulating means, and the space within the cup-shaped holders constituting a vacuum chamber. 95

6. In a lightning arrester, a pair of opposed metal, cup-shaped members having inwardly extending projections constituting electrodes, means including an insulating plate for spacing said opposed members apart, plastic means for holding said plate 100 and said members in fixed relation and for insulating them, the space between the opposed plates constituting a vacuum chamber. 105

7. In a lightning arrester, a pair of opposed metal cup-shaped members having central portions pressed inwardly toward one another and constituting electrodes, an insulating spacing plate provided with an opening, said disc having its edges disposed between the edges of the cup-shaped members, insulating plastic material covering the contiguous edges of the plate and the cup-shaped members for securing the parts in position and for insulating the cup-shaped members. 115 120

8. In a lightning arrester, a pair of opposed members, electrodes carried by said members, and an insulating spacing plate consisting of a series of insulating plates having registering openings of different 125 sizes.

9. In a lightning arrester, a pair of opposed members, electrodes carried by said

members, and an insulating spacing plate disposed between the edges of said electrode holders, said insulating plate having a recess of relatively narrow depth and relatively great diameter, and being provided with openings on each side of said recess.

10. In a lightning arrester, in combination, a pair of metal cup-shaped members

having inwardly projecting electrodes and a medianly arranged perforated insulating plate disposed between the rims of said cup-shaped members, and means retaining said rims in rigid connection with each other to constitute a closed casing.

In testimony whereof I affix my signature.
GEORGE FRANCIS GRAY.
